(57) **CLAIM**

The ornamental design for a tape dispenser, as shown and
described.

DESCRIPTION

FIG. 1 is a perspective view of a tape dispenser showing our
new design;

FIG. 2 is a left side view of the tape dispenser illustrated in
FIG. 1, the right side view being the mirror image thereof;
FIG. 3 is a top view of the tape dispenser illustrated in FIG.
1;

FIG. 4 is a bottom view of the tape dispenser illustrated in
FIG. 1;

FIG. 5 is a front view of the tape dispenser illustrated in FIG.
1; and,

FIG. 6 is a rear view of the tape dispenser illustrated in FIG.
1.

The structure depicted by means of broken lines in the
figures has been shown for illustrative purposes only and
forms no part of the claimed design.

The drawings are lined for color; specifically diagonal lines
represent green coloring and the elliptical shaped area
surrounding the central hole without lining represents white
coloring.
